(57) **CLAIM**

The ornamental design for a microphone with clip as shown and described.

DESCRIPTION

Reproduction 1.1 is a front view of a microphone with clip showing our new design;

Reproduction 1.2 is a left side view thereof;

Reproduction 1.3 is a right side view thereof;

Reproduction 1.4 is a bottom view thereof;

Reproduction 1.5 is a top view thereof;

Reproduction 1.6 is a back view thereof; and

Reproduction 1.7 is a perspective view thereof.

The broken lines are used to show portions of the microphone with clip that form no part of the claimed design.

1 Claim, 7 Drawing Sheets
